UNITED STATES PATENT OFFICE

2,454,068

VALVE SEAT GRINDER

William A. Kuhlman, Los Angeles, Calif.

Application December 26, 1946, Serial No. 718,396

2 Claims. (Cl. 51—205)

1

My invention relates to improvements in valve seat grinders and has for its principal objects, to provide a simple, practical and inexpensive device which may be conveniently used for rapidly and accurately grinding the valve seats of faucets, further, to provide a valve seat grinder having a manually operable shaft carrying at one end a grinding element such as a small, solid body composed of pulverized abrasive material such as emery, Carborundum or the like, having its lower end shaped so as to conform to the shape of the conventional valve seats of faucets, taps, spigots and the like and further, to mount on the shaft that carries the grinding member, a small sleeve which rests on the upper portion of the faucet or valve body, and provides a bearing for said shaft and thereby insuring accuracy of the valve seat grinding function.

A further object of my invention is to provide novel means for mounting a crank handle on the upper end of the grinder shaft.

With the foregoing and other objects in view, my invention consists in certain novel features of construction and arrangement of parts which will be hereinafter more fully described and claimed and illustrated in the accompanying drawings, in which:

Fig. 1 is a vertical section through the center of a faucet and showing my improved valve seat grinder in operative position thereon.

Fig. 2 is a detail section taken on the line 2—2 of Fig. 1.

Fig. 3 is a detail section taken on the line 3—3 of Fig. 1.

Fig. 4 is a detail section similar to Fig. 3 and showing a modified form of mounting the grinding member on the shaft.

Referring by numerals to the accompanying drawing which illustrates a preferred embodiment of my invention, 10 designates a shaft of any suitable length and diameter and composed of wood, plastics, composition or metal.

Formed in the upper end of shaft 10 is an axial bore 11 and leading from the upper end of said bore to the outer face of said shaft is a horizontally disposed notch 12.

Occupying bore 11 is the inner end member 13 of a small crank having the end portion of its intermediate arm 14, adjacent member 13, seated in notch 12.

Member 13 and adjacent portion of arm 14 are rigidly secured to shaft 10 by a suitable adhesive.

Mounted for rotation on the upstanding outer end member 15 of the crank, is a knob or small handle 16, of wood, plastics or metal.

2

Carried by the lower end of shaft 10 is a substantially cylindrical body 17 of abrasive substance such as pulverized emery, Carborundum or the like, same being moulded onto said shaft and to anchor said body to the shaft, the end of the latter may be provided with an inclined slot such as 18 which receives a portion of the body 17 when same is molded onto the shaft.

The anchoring of the abrasive body to the shaft 10 may be accomplished by forming a circumferential groove such as 19 in the lower portion of the shaft.

To conform to the angularity of valve seats the underface of body 17 adjacent the outer face of the body 17 is beveled as designated by 20.

To provide an adjustable bearing for shaft 10 while the grinder is in use, a collar 21, of rubber, or composition is mounted to slide and rotate freely upon said shaft and said collar preferably 20 tapers toward its lower end.

To use the grinder, the lower portion thereof is inserted in the valve housing, after the valve and its stem have been removed therefrom.

After the bevelled face 20 on the underside of member 17 has been positioned on the valve seat as seen in Fig. 1, collar 21 is moved down on shaft 10 until the lower portion of said collar enters and rests upon the upper portion of the valve housing.

30 Actuation of the crank shaft rotates shaft 10 and the rubbing action of the lower end of member 17 on the valve seat quickly and accurately grinds and re-faces said seat.

During the grinding operation just described, 35 collar 21 provides a firm and substantial bearing for shaft 10, thus holding same in stable operative position and insuring perfect grinding of the valve seat.

The use of a hard body of pulverized abrasive 40 material for re-facing valve seats eliminates chatter of the tool while in service, does not gouge or produce burrs on the seat and materially speeds up the grinding and re-surfacing operation.

45 Thus it will be seen that I have provided a valve seat grinding tool that is simple in structure, inexpensive of manufacture and very effective in performing the functions for which it is intended.

50 It will be understood that minor changes in the size, form and construction of the various parts of my improved valve seat grinder may be made and substituted for those herein shown 55 and described, without departing from the spirit

of my invention, the scope of which is set forth in the appended claims.

I claim as my invention:

1. In a valve seat grinding tool a shaft provided in its lower end with a notch, an abrasive body enclosing the lower end of said shaft with a portion embedded in said notch to anchor said body to said shaft, the upper end of said shaft being provided with an axial bore and a radial notch at the upper end of said bore, and a crank having inner end portions seated in said bore and notch.

2. The valve grinding tool as set forth in claim 1, with an elastic bearing forming member loosely mounted on said shaft.

WILLIAM A. KUHLMAN.
